Inventor

J. Whikehart,

By *John Whikehart*
Attorney

UNITED STATES PATENT OFFICE.

JOHN WHIKEHART, OF ZANESVILLE, OHIO.

GAS BURNER.

Application filed December 18, 1923. Serial No. 631,380.

To all whom it may concern:

Be it known that I, JOHN WHIKEHART, a citizen of the United States, residing at Zanesville, in the county of Muskingum and State of Ohio, have invented certain new and useful Improvements in Gas Burners; and I do hereby declare the following to be a full, clear, and exact description of the invention, such as will enable others skilled in the art to which it appertains to make and use the same.

The object of the present invention is the provision of means for utilizing gaseous fuel in furnaces, stoves and heaters of every description, said means being of such construction as to prevent the waste of fuel and to insure the utilization of a maximum amount of heat units from a given amount of fuel.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is an elevational view of a burner embodying the invention,

Figure 2 is a vertical central longitudinal section thereof, and

Figure 3 is a sectional view on the line 3-3 of Figure 1, looking to the right as designated by the arrows.

Corresponding and like parts are referred to in the following description and designated in the several views of the drawings by like reference characters.

The numeral 1 designates a header or manifold which is closed at one end by means of a cap 2 and at its opposite end by a cap 3 in which is formed an opening and having an intermediately threaded boss 4 in line with the opening to which a pipe (not shown) may be coupled for supplying fuel to the burner. A plurality of nipples 5 are threaded into a side of the header 1 and are

preferably in line and regularly spaced. Burner tubes 6 are threaded to the projecting ends of the nipples 5 and are provided in their sides with openings 7 for the admission of air to mix with the jets of gas issuing from small openings 8 formed in plates 9 disposed within the tubes 6 at a point below the air inlets 7. The burner tubes 6 may be of any preferred construction and material and the plates 9 may be provided in any manner common in the art. A shield 10 is disposed above the header 1 and is preferably mounted upon burner tubes 6, the upper portion of the latter being reduced to provide shoulders 11 which engage and support the shield 10, the latter being provided with openings of a size and in position to register with the upper reduced ends of the burner tubes. A bridle 12 engages opposite edge portions of the shield 10 and passes beneath the header 1 and serves to prevent displacement of the shield, while admitting of the same being readily removed when required. The shield preferably consists of metal and is transversely curved and operates to prevent the heat from the flame interfering with the proper ingress of air through the openings 7 so as to mix with the gaseous fuel issuing from the outlets 8.

It will be understood from the foregoing that the burner is simple in construction and may be of any required length and may be readily installed in the furnace of a heating plant or in the firebox of a cooking stove or heater.

What is claimed is:

1. A burner for gaseous fuel comprising a header, burner tubes at intervals in the length of the header, each burner tube having an air inlet opening on each side and a plate provided with a minute fuel outlet and located in the tube below the air inlet openings, a connection below each plate between the burner tubes and header, and a shield supported by the burner tubes and disposed between the outlets thereof and the air inlet openings.

2. A burner for gaseous fuel comprising a header, nipples let into openings formed in a side of the header, burner tubes fitted to the nipples and having air inlet openings

in their sides, each tube having a plate with a minute fuel outlet between each nipple and said air inlet openings, the burner tubes having their outer ends reduced, and a shield mounted upon the reduced ends of the burner tubes and supported by the shoulders formed at the inner ends of the reduced portions.

In testimony whereof I affix my signature in presence of two witnesses.

JOHN WHIKEHART.
Witnesses:

LOUIS H. GREEN,
J. M. DONAHOE.
